ARTHUR H. LANGMAN, OF DENVER, COLORADO, ASSIGNOR TO ARTHUR C. LEISENRING, OF DENVER, COLORADO

GAS SAVER AND CARBON REMOVER

Application filed May 4, 1929. Serial No. 360,419.

This invention relates to improvements in that type of apparatus usually referred to as gas savers.

It is the object of this invention to produce a device of a simple construction that can be readily applied to the intake manifold of an internal combustion engine and by means of which the interior of the manifold can be connected with the interior of the crank case of the engine, for the purpose of sucking gas and vapors from the crank case and mixing the same with the fuel mixture that passes from the carburetor to the engine cylinders.

15 During the operation of an internal combustion engine, a considerable amount of the gasoline or liquid fuel, which is vaporized and transferred to the engine cylinders, will pass by the piston and into the crank case 20 during the operation of the engine. The hydrocarbon gases that escape from the combustion chamber of the cylinders to the crank case represent a considerable loss and besides this these vapors, after they reach the crank 25 case condense and the gasoline becomes mixed with the lubricating oils and destroys its lubricating properties.

It is evident that if the vapors that escape from the cylinders into the crank case 30 can be returned to the intake manifold they will again enter the cylinders together with the new fuel mixture and in this manner the energy which they contain will finally be transformed into useful work. It is also evident that if these gases or vapors are removed 35 from the crank case as fast as they enter, that there will be no opportunity for them to condense and therefore the gasoline which they contain will not have an opportunity 40 to become mixed with the lubricating oil.

This invention, briefly described, consists of an elongated tube, whose sides are provided with a plurality of perforations spaced along the length of the tube and within 45 which is located a plunger that can be reciprocated so as to cover or uncover these openings. A tubular member surrounds that portion of the tube which contains the openings and has a larger inner diameter than 50 the outer diameter of the tube so as to provide

an annular cylindrical chamber between the outer surface of the tube and the inner surface of the tubular member. The ends of the tubular member are connected with the outer surface of the tube so as to close the ends of the annular chamber. One end of the tube is connected with the interior of the intake manifold and the annular chamber is connected with the breather pipe of the engine by means of a flexible copper tube. 55 A small valve comprising a funnel is also connected with the interior of the annular chamber and serves as a means for introducing kerosene or other liquid into the engine cylinders for the purpose of removing carbon and for the purpose of priming the engine in case it is found difficult to start the same during cold weather.

Having thus briefly described the invention, the same will now be described in detail 70 and for this purpose reference will be had to the accompanying drawing in which the preferred embodiment thereof has been illustrated and in which:

Fig. 1 is a side elevation of an internal combustion engine showing my gas saver in place thereon;

Fig. 2 is a fragmentary view showing the gas saver connected in the line from the intake manifold to the vacuum tank;

Fig. 3 is a longitudinal section through my improved gas saver; and

Fig. 4 is a section taken on line 4—4, Fig. 3, parts being broken away to better show the construction.

In the drawing numeral 1 represents an internal combustion engine provided with a crank case 2 having a breather pipe 3 in connection therewith. Numeral 4 represents the intake manifold, 5 the exhaust manifold, and 6 the carburetor, while numeral 7 represents a vacuum tank of the ordinary construction.

My improved gas saver consists of a tube 8 which is provided with a plurality of openings 9 spaced longitudinally thereof. A plunger 10 is slidable in the inside of the tube and serves to cover the openings 9 and to uncover the same. This plunger is of such length that when it is in its innermost position, all of the openings 9 will be closed. One

end of tube 8 is provided with a threaded portion 11 that can be connected with a threaded opening in the wall of the intake manifold. A tubular member 12 having ends 13 and 14 that are provided with openings of the proper size to receive the tube 8, encloses that portion of the tube which has the openings 9. The inside diameter of tubular member 12 is greater than the outside diameter of tubes 8 and therefore an annular chamber 15 is provided which is in communication with the inside of tube 8 through openings 9. Member 12 is provided with diametrically located bosses 16 and 17 which have threaded openings. The opening in boss 17 has connected therewith a coupling 18 that is secured to one end of the tube 19. The other end of this tube is in communication with the interior of the crank case through the breather pipe 3. The reason why tube 19 is connected with the breather pipe instead of directly with the crank case is that if it were connected directly with the crank case a lot of oil spray would be carried away mixed with the vapors and this would be objectionable, whereas, by being connected with the breather pipe, very little, if any oil, will be carried away when the device is in operation. Connected with the opening in boss 16 is a valve member comprising two parts 19 and 20. The part 19 is made in the form of an L, while part 20 is made in the shape of a funnel. The outer end of member 19 has a threaded opening 21 which terminates in a smaller opening 22. Member 20 has a threaded portion 23 that cooperates with the threaded surface of opening 21 and terminates in a conical end 24 that cooperates with the valve seat to close the opening. An opening 25 extends from the bottom of the recess 26 to the outside of member 24. By turning member 20, the interior of the cup or recess 26 can be put in communication with the annular chamber 15. A wire 27 is connected with the outer end of the plunger 10 and is held in place by means of a set screw 18. This wire passes through a tube 29 and is connected with a handle 30 that is carried by the instrument board 31. When the handle 30 is pulled outwardly or to the left in the drawing, the plunger 10 is moved outwardly so as to uncover the holes 9. The holes 9 are uncovered one at a time, and therefore the effective area of the openings 55 between the interior of tube 8 and the annular chamber 15 can be varied to any extent desired. When the engine is provided with a vacuum tank, the gas saver is connected to the vacuum line, by means of a T in the manner shown in Fig. 2.

Let us now assume that the engine is in operation and that the plunger 10 is moved so as to uncover a plurality of the openings 9. The interior of chamber 15 will now be placed in communication with the interior

of the manifold and as the pressure in the manifold is less than atmospheric, gas and vapor will flow from the crank case through tube 19 into chamber 15 and thence through the openings 9 into the manifold. This action will remove from the crank case the gaseous vapors and return them to the engine, thereby preventing the condensation of gasoline within the crank case.

If it is necessary to prime the engine when starting on a cold morning, this can be readily done by opening the valve 20 and pouring gasoline or other volatile hydrocarbon liquid into the cup 26 and then operating the starter whereby the priming liquid or vapors therefrom will be transferred to the cylinders.

It is well known that carbon accumulates to a considerable extent within the cylinders of an internal combustion engine, and when this occurs, it can be quite readily removed by introducing a considerable quantity of kerosene through valve 20 and letting the engine remain idle for several hours. When the engine is again started, the carbon which has been loosened by the action of the kerosene will be blown out by the exhaust valves.

From the above description it will be apparent that I have produced a very simple and substantial gas saver which can be readily applied to an engine and which can be easily regulated by the driver so as to obtain the best results under the various operative conditions. In order to obtain the most desirable results the driver must be in position to vary the amount of air or vapor introduced as it is necessary to have a richer mixture when the car is running slowly than when it is running at a high speed and this can best be obtained by means of a manually controlled valve of the type herein described.

Having described the invention what is claimed as new is:

1. A device of the class described, comprising an elongated tube having a plurality of openings therein, a tubular member surrounding the tube and having its ends connected therewith, the interior diameter of the tubular member being greater than the outside diameter of the tube whereby an annular chamber is formed, a plunger located within the tube and slideable therein to cover and uncover one or more of said openings, the tubular member having an opening therein which is adapted to be connected with the crank case of an engine.

2. In an internal combustion engine having an intake manifold and a crank case, a gas saver comprising an elongated tube having one end in communication with the manifold, the wall of the tube having a number of openings spaced along its length, a plunger slideable in the tube and adapted to cover and uncover the openings, a tubular member enclosing a portion of the tube, the inside diameter of the tubular member being greater

than the outside diameter of the tube whereby an annular chamber is formed, means for connecting the interior of the annular chamber with the interior of the crank case and 5 means for reciprocating the plunger.

3. In an internal combustion engine having an intake manifold and a crank case, a gas saver comprising an elongated tube having one end in communication with the manifold, the wall of the tube having a number of openings spaced along its length, a plunger slideable in the tube and adapted to cover and uncover the openings, a tubular member enclosing a portion of the tube, the inside diameter of the tubular member being greater than the outside diameter of the tube whereby an annular chamber is formed, means for connecting the interior of the annular chamber with the interior of crank case, means for 15 introducing a liquid into the annular chamber and means for reciprocating the plunger.

4. A device of the class described comprising, an elongated tube provided with a plurality of openings along its length, a tubular member enclosing a portion of said tube, the inside of the tubular member being spaced from the outside of the tube whereby a chamber is formed between the two, means for closing the opening between the ends of the tubular member and the tube, the tubular member having two openings, one of which is adapted to receive a priming cup and the other of which is adapted to be connected with the crank case of an internal combustion 20 engine, a plunger slideable in the tube and 25 means for reciprocating the plunger.

In testimony whereof I affix my signature.
ARTHUR H. LANGMAN.
